UNITED STATES PATENT OFFICE

2,598,346

AUTOMATIC GAS SHUTOFF DEVICE FOR
PRINTING PRESSES

William F. Burke and Robert L. Essex, Athens,
Ohio, assignors to The McBee Company,
Athens, Ohio, a corporation

Application September 8, 1947, Serial No. 772,673

5 Claims. (Cl. 101—416)

1

The present invention relates to presses, and is more particularly directed to heating devices for rapidly drying printed matter on paper and like materials.

Some printing presses incorporate a heating device, usually one or more gas burners arranged transversely of the direction of travel of the paper through the press, for rapidly heating or drying the matter impressed on the paper by the printing rolls. The rate at which the paper travels over the burners is so chosen as to insure heating or drying of the matter without exposing the paper to the heat for a sufficient period as to cause its ignition or charring. The gas passes to the burners through an electrically controlled valve, which is closed automatically upon opening the circuit to the press drive motor or motors, for the purpose of stopping the press feed and shutting off the gas flame. At times, the accumulated gas in the lines between the valve and burner outlets is sufficient to continue burner operation during the slowing and arresting of the paper's travel through the press, allowing the gas flame to ignite the paper.

The present invention has for an object the provision of a device for preventing continued application of the flame or other heat source, to the paper upon arresting the printing press operation.

Another object of the invention is to provide a device which closes the burner outlets upon opening of the printing press motor circuit, thereby preventing any gas accumulation between the main gas valve and burner outlet from sustaining the flame.

The invention is exemplified in the following description and illustrated by way of example in the accompanying drawings, in which:

Fig. 1 is a diagrammatic view of a printing press embodying a form of the present invention.

Fig. 2 is an isometric view of a portion of the gas burner and the burner outlet closing device.

Fig. 3 is a combined side elevational and cross-sectional view of the gas burner device in open position.

Fig. 4 is a view similar to Fig. 3 with the gas burner device in closed position.

As disclosed in the drawings, the invention has been applied to a printing press modified to print wax carbon spots 10 on paper 11. The web of paper 11 is fed from a suitable supply over guide and feed rolls 12 and between a lower printing roll 13 and an upper impression roll 14, then passing over one or more gas burners 15 extending transversely of the direction in which the

2

paper is being fed, and thence continuing around adjacent chilled rolls 16 and over an upper guide roll 17. The wax carbon material is fed from a fountain 18 onto an ink roll 19, which suitably applies the material onto the printing roll 13, which, in turn, impresses it upon the underside of the web 11.

The rolls are appropriately synchronized in speed and the paper web is fed past the burners 15 at such a rate as to insure remelting of the low melting point waxes in the wax carbon spots impressed upon the web, the rate of travel of the web being such as to prevent its ignition by the gas burner flames. If ordinary printed areas were marked on the paper, the printing ink would be dried upon feeding of the paper past the burners 15.

The gas is fed through an inlet pipe 20 into a main gas valve 21, which may be electrically controlled, as by means of a solenoid (not shown), from which the gas flows into a main header 22 and into branch pipes or lines 23 leading to the burners 15. Actually, there is a suitable valve 25 and air inlet for each burner, of usual arrangement, that is not disclosed since it does not, by itself, form any part of the present invention. The burners 15 extending transversely of the web of paper are provided with longitudinally spaced holes 24 or perforations through which a mixture of the air and gas may pass and burn above the hole outlets.

The main gas valve 21, as aforesaid, is electrically controlled, the electrical control mechanism being in the same circuit as the electrical connections leading to a driving motor 25 of the printing press. When the circuit to the motor 25 is open, the circuit to the electrical mechanism for operating the main gas valve 21 is also open, causing such valve to shut off the supply of gas to the header 22 and the branch lines 23.

It is to be noted that the header 22 and branch lines 23 will contain a definite volume of gas and air following closing of the main valve 21. This air and gas is sufficient to support combustion at the gas burner outlets 24 during the time that the paper 11 is coming to rest following opening of the drive motor circuit, slowing down the speed of travel of the paper web, and allowing its potential ignition by the flames, which will continue burning until a substantial portion of the gas and air accumulation in the lines running from the main gas valve has been consumed.

The present invention avoids the hazard of igniting of charring the paper web. To achieve

this purpose, each gas burner pipe 15, which is carried from the frame (not shown) of the printing press in suitable brackets 26, has a tubular closure or baffle 27 oscillatably mounted thereon and extending along substantially its entire length. Each closure member 27 is provided with a slot or opening 28 extending longitudinally throughout the length of the burner holes 24. The tubular member may be shifted to align its slot 28 with the burner holes 24, allowing the gas and air mixture to issue from the latter and support the flame, or, it may be shifted to a position in which the closure 27 covers the holes 24 and shuts off the gas and air flow.

The mechanism for selectively positioning the tubular closure or flame baffle 27 in the manner described above may consist of an operating lever 29 secured to each tubular closure member, with its free end pivotally connected to a common rod 30 by means of a pin 31. One end of this rod is, in turn, connected to an arm 32 of a bell crank lever 33 through a pin 34 and slot 35 connection, which lever is pivoted upon a pin 36 suitably secured to the frame of the press. The other arm 37 of the lever is connected to the plunger 38 of a solenoid 39 through a pin 40 and slot 41 connection, the solenoid coil being electrically connected in parallel with the main gas valve 21 and motor 25. Energization of the solenoid 39 pulls its plunger 38 inwardly of the coil and rocks the bell crank lever 33 in such direction as to shift the rod 30, the operating levers 29 and the closures 27 simultaneously to positions in which the longitudinal slots 28 through the tubular closure members are in alignment with the burner outlets 24, allowing the air and gas mixture to issue from the burners and sustain the flame under the paper web 11. This position of the closure members 27 is determined by engagement of a pin 42 secured to each burner 15 with the end of an arcuate slot 43 in each closure member 27. Deenergizing of the solenoid coil allows a tension spring 44 secured to the other end of the rod 30 to shift it in the opposite direction, rocking the operating levers 29 and the tubular closure members 27 on the gas burners 15 to positions determined by engagement of the pins 42 with the outer ends of the slots 43, where the longitudinal openings 28 in the closure members are disaligned with the gas burner outlets 24, closing the latter and extinguishing the flames.

Normally, while the press is not running, the spring 44 maintains the tubular closure or baffle members 27 in closed position over the burner outlets 24. Upon starting of the printing press, the main gas valve 21 and the solenoid 39 are energized to cause opening of the main gas valve and the shifting of the tubular closure members 27 to open position, allowing the gas to pass through the main valve 21 and into the header 22 and branch lines 23 to support the flame on the burners 15. The gas flames can then perform the resulting operation on the wax carbon spots 10 printed on the web of paper 11, or the drying operation of printed ink on the paper. Immediately upon opening of the printing press motor circuit, the solenoid 39 is deenergized, which allows the spring 44 to move the tubular members 27 to closed positions over the burner outlets 24, immediately extinguishing the gas flames, and preventing their continued action on the web of paper, regardless of any accumulation of gases which may exist between the main gas valve 21 and the burner outlets 24. In this

fashion, assurance is had against continued exposure of the slowly moving web, or completely arrested web, to flame action, preventing its charring and possible ignition.

Although particular reference has been made in this description to presses for printing wax carbon spots on a continuous web of paper, it is to be understood that the invention is applicable to presses for printing other matter on paper and similar materials, and that the paper and the like may be in sheet, as well as web, form.

Attention is directed to our application for "Method and Apparatus for Applying Wax Carbon Spots on Paper Sheets," Serial No. 772,674, filed September 8, 1947, which describes and claims the feature disclosed herein of heating the web with wax carbon compound applied thereto after it leaves the impression rolls, to obtain a uniform surface on each wax carbon spot devoid of high and low spots.

While we have illustrated and described our invention in detail, it is to be understood that various changes may be made therein by those skilled in the art without departing from the spirit of the invention as defined in the appended claims.

Having thus described our invention, what we claim and desire to secure by Letters Patent is:

1. A printing press, including means comprising an electric motor for feeding paper, a burner having an outlet disposed adjacent the paper as it is being fed through the press for heating said paper, closure means adapted to close said outlet and completely extinguishing the flame at the outlet, and means in the same electric circuit as said motor for holding said closure means open in response to passage of current through said circuit, and means for shifting said closure means to outlet closing position upon opening of said circuit.

2. A printing press, including means comprising an electric motor for feeding paper through said press, a burner having an outlet disposed adjacent the paper as it is being fed through the press, closure means adapted to close said outlet and completely extinguishing the flame at the outlet, a solenoid connected in the same electric circuit as said motor, means connecting said solenoid with said closure means whereby said solenoid moves said closure means to open position in response to passage of current through said circuit, and a spring attached to said connecting means for shifting said closure means to outlet closing position upon opening of said circuit.

3. A printing press, including means comprising an electric motor for feeding paper through said press, a burner having an outlet disposed adjacent the paper as it is being fed through the press, closure means adapted to close said outlet and completely extinguishing the flame at the outlet, a main valve connected in the same electric circuit as said motor for determining the flow of gas to said burner, a solenoid connected in said circuit, means connecting said solenoid with said closure means, a spring attached to said connecting means, said main valve being in open position and said solenoid shifting said closure means to outlet opening position upon passage of current through said circuit, opening of said circuit enabling said main valve to close and said spring to shift said closure means to outlet closing position.

4. A printing press, including means comprising an electric motor for feeding paper through

said press, a burner having an outlet disposed adjacent the paper as it is being fed through the press, tubular closure means disposed over said burner for selectively opening and closing said outlet to completely extinguish the flame at the outlet, a solenoid operatively connected to said means and connected in the same electric circuit as said motor, whereby said solenoid moves said closure means to open position in response to passage of current through said circuit, and a spring attached to said means for shifting it to outlet closing position upon opening of said circuit.

5. A printing press, including means comprising an electric motor for feeding paper through said press, a plurality of burners disposed adjacent the paper and having outlets from which gas may issue and burn for heating matter on said paper, a tubular closure member disposed over each burner for selectively opening and closing its outlet to completely extinguish the flame at the outlet, means connecting said members for simultaneous movement to open and closed positions, a solenoid operatively con-

nected to said means and connected in the same electric circuit as said motor whereby said solenoid moves said closure members simultaneously to open position in response to passage of current through said circuit, and a spring attached to said means for shifting said members simultaneously to outlet closing position upon opening of said circuit.
